UNITED STATES PATENT OFFICE.

JAMES E. CUFF, OF CHICAGO, ILLINOIS, ASSIGNOR TO AMERICAN FLYER MANUFACTURING COMPANY, OF CHICAGO, ILLINOIS, A CORPORATION OF ILLINOIS.

DESIGN FOR A TOY WATCHMAN'S TOWER.

Application filed June 2, 1928. Serial No. 26,965. Term of patent 7 years.

To all whom it may concern:

Be it known that I, JAMES E. CUFF, a citizen of the United States, residing at Chicago, in the county of Cook and State of Illinois, have invented a new, original, and ornamental Design for Toy Watchman's Tower, of which the following is a specification, reference being had to the accompanying drawing, forming part thereof.

The figure is a perspective view of the toy watchman's tower showing my new design.

I claim:—

The ornamental design for a toy watchman's tower, as shown.

JAMES E. CUFF.
